UNITED STATES PATENT OFFICE.

WALTER ERBEN, OF PHILADELPHIA, PENNSYLVANIA.

PROCESS OF EXTRACTING GREASE FROM WOOL.

SPECIFICATION forming part of Letters Patent No. 669,955, dated March 12, 1901.

Application filed May 12, 1899. Serial No. 716,548. (No specimens.)

To all whom it may concern:

Be it known that I, WALTER ERBEN, a citizen of the United States, residing in Philadelphia, Pennsylvania, have invented certain 5 Improvements in Methods of Extracting Grease from Wool, of which the following is a specification.

The object of my invention is to provide an efficient method of extracting grease from 10 wool by means of naphtha or other suitable solvent, an object which I attain in the manner hereinafter set forth, reference being had to the accompanying drawings, in which—

Figure 1 is a representation in diagrammatic form of apparatus constructed in accordance with my invention, and Fig. 2 is a longitudinal sectional view of part of the extracting-keir and mechanism used in connection therewith.

20 The extraction of grease from wool by means of naphtha or equivalent solvent of grease has been many times proposed, but has not, so far as I am aware, been extensively used in practice, one of the objections to the process 25 being the highly-inflammable character of the solvent, another being the difficulty of removing all traces of the solvent from the wool after the grease has been extracted therefrom, and still another being the expensive char- 30 acter of the apparatus designed for carrying out the process. My invention has therefore been devised with the view of overcoming these objections, the apparatus used by me being represented in the accompanying drawings, in which—

35 A represents the extracting vessel or keir and B, C, D, and E a series of vessels for containing the naphtha or other solvent which is being used and which will hereinafter be re- 40 ferred to simply as "solvent."

In connection with the extracting-keir and solvent-tanks are employed a vacuum-pump F, a solvent-pump G, a high-pressure water-pump H, a solvent-heater I, solvent-stills J 45 and K, with their condensers L and M, an evaporator N to recover potash from the water used for washing the wool in the keir, a heater P for said water, and a condenser S for any solvent-vapor that may be withdrawn 50 from any part of the apparatus by the vacuum-pump.

In connection with the solvent vessels are

used five mains a, b, c, d, and f, each of these mains communicating with each of the solvent-tanks through a suitable valved branch, 55 the main a constituting a vacuum-main and being in communication also with the condenser S, with the vacuum-pump, with the upper and lower portions of the keir, and with the still J. The main b is the solvent-supply 60 main, and in said main is introduced the solvent-pump G and the solvent-heater I, this main communicating with the lower portion of the keir and also with the lower portion of the solvent-still K. The main c is a solvent- 65 return main, communicating with the bottom of the keir and also with the solvent-pipes of the condensers L and M. The main d is also a solvent-return main, communicating with the upper portion of the extracting-keir. The 70 main f is a transfer-main connecting each of the solvent-tanks with the main b, where it issues from the solvent-pump, whereby solvent may be transferred from any one of the solvent-tanks to any other one of the same, 75 as desired.

A pipe g leads from the lower portion of the extracting-keir to the lower portion of the solvent-still J, a branch h of this pipe leading to the sewer or other waste-outflow and 80 another branch i leading to the evaporator N. A pipe j leads from the upper portion of the extracting-keir to the solvent-still J, and a pipe k serves to convey grease from the bottom of the solvent-still K to a grease-recep- 85 tacle, (not shown in the drawings, but located at any suitable point.) A pipe m leads from the elevated reservoir and water-heater P to the lower portion of the extracting-keir. The tank S in the vacuum-main a has a cold-wa- 90 ter coil or other cooling device, so as to con- dense any solvent-vapors which may be drawn into said tank, and the discharge-pipe of the vacuum-pump may also, if desired, be pro- 95 vided with such a cooling or condensing tank.

Valves 1 and 2 in the main a control com- 100 munication between the vacuum-pump and the upper portion of the extracting-keir, the two valves being employed, so as to open or close communication either from a point ad- jacent to the keir or from a point adjacent to the pump. Valves 3 control the com- munication between each solvent-tank and the solvent-pump, a valve 4 governs the discharge

from said pump into the main *b*, and a valve 5 governs the discharge from the solvent-pump into the main *f*. Valves 6 and 7 determine whether the discharge from the solvent-pump shall be directed to the solvent-heater *I* or to the solvent-still *K*, and a valve 8 governs the communication between the solvent-heater and the lower portion of the extracting-keir. A valve 9 governs communication between the upper portion of the extracting-keir and the solvent-return main *d*, and valves 10 control communication between said main and the solvent-tanks. A valve 11 governs the flow through a pipe *n*, which leads from the high-pressure pump *H* to a cylinder 37, forming part of a ram used in connection with the keir, as described hereinafter. A valve 12 governs the flow from the lower portion of the extracting-keir to the solvent-return main *c*, and valves 13 govern communication between said main and the various solvent-tanks, a valve 14 controlling the flow of solvent from the condenser *L* into said return-main *c*. A valve 15 is interposed in the vacuum-main *a* between the solvent-tanks and the vacuum-pump, and valves 16 control the communication between said vacuum-main and the different solvent-tanks, a valve 17 controlling communication between the vacuum-pump and the solvent-still *J*. A valve 18 governs the flow of water through the pipe *m* from the elevated reservoir *P* into the lower portion of the extracting-keir, and a valve 19 governs the flow through the pipe *j* from the upper portion of the extracting-keir to the solvent-still *J*. A valve 20 governs the flow from the lower portion of the keir into the pipe *g*, a valve 21 governing the flow from said pipe to the sewer, a valve 22 governing the flow from said pipe to the still *J*, and a valve 23 governing the flow from said still *J* through the pipe *i* into the evaporator *N*. A valve 24 governs the flow from the still *J* to the condenser *L*, the flow from the condenser *M* into the solvent-return main *c* being controlled by a valve 25 and the flow from the still *K* through the grease-discharge pipe *k* being governed by a valve 26. Valves 27 govern communication between the transfer-main *f* and the various solvent-tanks, and a valve 28 governs communication between the vacuum-main *a* and the lower part of the extracting-keir.

The extracting-keir *A* has at the top an annular chamber *s*, which is in communication with the interior of the keir through a perforated plate *t*, carried by the removable cap or cover *v* of the keir, and through channels formed in the under side of said cap or cover. The lower portion of the keir is combined with a ram carrying a movable perforated plunger or false bottom, the construction of this portion of each keir being represented in the enlarged view, Fig. 2, in which 30 represents said false bottom, which is in the form of a piston or plunger, fitted to the interior of the keir so as to slide freely therein and having

a perforated horizontal web 31, on which is supported a perforated grate 32, the web 31 having a central hub 33, which is supported, preferably by means of a ball-and-socket joint, upon the upper end of the plunger 34 of the ram, a bolt 35 serving to confine the false bottom vertically to said plunger. 70

To the bottom plate 36 of the keir is bolted 75 the upper end of the ram-cylinder 37, which has a stuffing-box casing 38, through which passes the ram or plunger 34, said stuffing-box casing having a follower 39, as usual, for compressing the packing therein. With the upper portion of the ram-cylinder 37 communicates the pipe *n*, leading to the high-pressure pump.

It will be understood that the keir, the stills, and the various solvent-tanks which I use in carrying out my invention are intended to be provided with gage-glasses, try-cocks, vacuum-breakers, air-vents, safety-valves, sight-boxes, and such like details, which it has not been deemed necessary to illustrate because of the small scale of the drawings, and it is preferable to connect all vents through which solvent-vapor can escape with a single main leading to any convenient point where such vapor can be either condensed or carried to the outside of the apartment in which the operations are being carried on, so that there will be no accumulation of solvent-vapor in said apartment. 90

The operation of the apparatus is as follows: 100 The false bottom of the keir being lowered to its full extent, the wool is placed in the keir and the cover of the same is fastened on. The vacuum-pump is then started, and valves 1, 2, 4, 6, 8, and 9 are opened. When the desired partial vacuum in the keir has been obtained, the valves 3 and 10 of one of the solvent-tanks—say the tank *B*—are opened, and the solvent-pump *G* is started, thereby drawing solvent from said tank *B* and forcing the same through the solvent-heater into the lower portion of the keir. The particular form of solvent-heater *I* have shown in the drawings is of the well-known tubular type, in which the steam or other heating agent passes 115 through a chamber crossed by the tubes through which the solvent is caused to flow, and it will be evident that the degree of temperature imparted to the solvent can be readily regulated by correspondingly regulating 120 the rate of flow of the solvent through the tubes or by regulation of the flow of the heating agent through the chamber crossed by said tubes. When the keir is almost full of solvent, the vacuum-pump is stopped and the valves 1 and 2 are closed to prevent solvent being drawn 125 into the vacuum-pump, the solvent-pump still continuing to run until the keir is full and overflows by main *d*, valves 9 and 10 being open, into tank *B*. If the wool is not sufficiently 130 degreased by this one charge of solvent, another charge is put through by merely closing valves 3 and 10 on tank *B* and opening valves 3 and 10 on tank *C*, and so on until the

wool is thoroughly degreased. After the wool has been degreased all of the valves previously open are closed, and the valve 12 and a valve 13 of one of the tanks B, C, D, or E are opened, so that the solvent may be permitted to drain back into said tank through the main c. When the wool is well drained, the valve 11 in the pipe n is opened, and the pump H is started, so as to force water under pressure into the ram-cylinder 37, thereby elevating the false bottom of the keir and compressing the wool against the perforated plate of the cover. The solvent thus expressed from the wool flows back through main c and valves 12 and 13 to the solvent-tank, and the draining of the wool is facilitated by starting the vacuum-pump and opening the valve 15 and the valve 16 of the tank into which the solvent is being drained, so as to create a partial vacuum in said drainage-receiving solvent-tank and in the keir. Such solvent as may have entered the annular chamber at the top of the keir can be permitted to flow back into its proper tank by way of the main d and valves 9 and 10. The valves on all pipes communicating with the interior of the keir being now closed, the false bottom is caused to descend and the wool thus permitted to expand or loosen up, the valve 17 being then opened and the vacuum-pump started. When sufficient vacuum has been obtained in the still J, the valves 18 and 19 are opened, and the heated water from the elevated tank P flows into and through the keir and carries with it the remaining traces of solvent contained in the mass of wool, at the same time dissolving and carrying along with it the potash salts usually associated with the wool. The mixture of water and solvent flows into the still J, and when the washing operation has been continued as long as desired the pump H is started, the valve 11 is opened, the false bottom of the keir is raised, and the wool is compressed. The valve 18 being still open, water fills the keir below the false bottom as the latter rises, so that all of the water and solvent remaining in the wool will be compelled to escape from the top of the keir, so as to enter the still J, no solvent being lost by permitting the expressed water and solvent to run into the bottom of the keir as the false bottom is raised. The valves 18, 19 are now closed and the valves 20 and 21 opened, so as to permit the water now contained in the keir, and which contains neither solvent nor potash, to escape to the sewer. The valve 22 is provided, however, in case it is desired to run this water into the still J instead of into the sewer. The opening of the valve 19 permits water which may be in the channel at the top of the keir to run into the still J through the pipe j. All of the valves previously opened being now closed, the false bottom of the keir is lowered, the vacuum-pump is started, and the valve 28 is opened, so as to create a partial vacuum in the keir, and air being permitted to enter the upper portion of the keir to break

this vacuum the cover is removed and the false bottom of the keir is again raised, so as to force the wool out of the same, the downward flow of air through the wool preventing the escape of any fumes or vapors, which might otherwise arise therefrom. The solvent distilled from the mixture of water and solvent in the still J is condensed and run back into any desired one of the solvent-tanks through the main c and valves 14 and 13, and the water remaining in the still is run into the evaporator N through the pipe i and valves 22 and 23 in order to recover the potash. 70

When the solvent contained in any one of the solvent-tanks becomes saturated with grease and it is desired to distil the same, the valves 3, 4, 7, and 25 are opened, as well as the valve 13 of that tank into which it is desired to return the distilled solvent, the greasy solvent being pumped into the still K through the main b, the vaporized solvent being condensed in the condenser M and returned to the desired tank through the main c and valves 25 and 13 and the grease remaining in the still K being run off to the grease-tank through the pipe k and valve 26. 80

A separate pump may be used for conveying the greasy solvent from the solvent-tanks to the still K, and a pump may be used for circulating the water through the keir, although I prefer to employ the elevated reservoir of heated water and to draw the same through the wool by creating a partial vacuum in the keir. Cold water may be used if the keir has means of heating the water after it has been introduced therein. 95

An important feature of my invention is the heating of the solvent prior to its action upon the wool, for I have found that when this is done not only am I enabled to remove the grease from the wool, but also to remove what is known as the "yolk" and "suint." If this is not removed, the hot water subsequently introduced into the keir to remove the solvent remaining in the wool will combine with said solvent, yolk, and suint to form an emulsion, which not only prevents the circulation of the water through the mass of wool but also seriously interferes with it if it does not actually prevent the subsequent washing and scouring of the wool. 110

I have found that in order to obtain the best results with 72° naphtha the temperature of the solvent employed should be about 100° Fahrenheit and the temperature of the water used to remove the remaining traces of solvent from the wool should be about 130° Fahrenheit, and while my invention is not limited to the use of the solvent and wash-water at such temperatures they are preferred. 120

I do not herein claim the process described except when that process involves the use of heated solvent or heated solvent and heated wash-water or the introduction of water into 130

the keir when the false bottom is being raised to express the surplus wash-water and solvent from the mass of wool, as the process excluding such features forms the subject of 5 an application filed by me on the 19th day of February, 1901, under Serial No. 47,945.

I do not in this application claim the apparatus herein disclosed for extracting grease from wool, as such apparatus forms the subject-matter of my divisional application for 10 a patent, filed January 26, 1901, Serial No. 44,861.

Having thus described my invention, I claim and desire to secure by Letters Patent—

1. An improvement in the art of extracting grease from wool by means of volatile liquid solvent in a closed vessel, said improvement consisting in first forcing or drawing heated 20 liquid solvent through the mass of wool, then expressing surplus solvent from the wool by mechanical pressure, then releasing the wool from such pressure, then forcing or drawing water through the wool in order to remove 25 the remaining traces of solvent therefrom, and then expressing surplus water from the wool by mechanical pressure, substantially as specified.

2. An improvement in the art of extracting 30 grease from wool by means of volatile liquid solvent in a closed vessel, said improvement consisting in first forcing or drawing through the mass of wool, solvent heated to a uniform temperature then expressing surplus solvent 35 from the wool by mechanical pressure, then releasing the wool from such pressure, then forcing or drawing water through the wool in order to remove the remaining traces of solvent therefrom, and then expressing sur-

plus water from the wool by mechanical pressure, substantially as specified. 40

3. An improvement in the art of extracting grease from wool by means of volatile liquid solvent in a closed vessel, said improvement consisting in first forcing or drawing heated 45 liquid solvent through the mass of wool, then expressing surplus solvent from the wool by mechanical pressure, then releasing the wool from such pressure, then forcing or drawing heated water through the wool in order to remove 50 the remaining traces of solvent therefrom, and then expressing surplus water from the wool by mechanical pressure, substantially as specified.

4. An improvement in the art of extracting 55 grease from wool by means of volatile liquid solvent in a closed vessel, said improvement consisting in first forcing or drawing heated liquid solvent through the mass of wool to extract the grease, then expressing surplus 60 solvent from the wool by mechanical pressure, then releasing the wool from such pressure, then forcing or drawing heated water through the wool in order to remove the remaining traces of solvent therefrom, and then 65 expressing surplus water from the wool by mechanical pressure applied to the bottom of the mass, and introducing water beneath the mass as it is being compressed, substantially as specified.

In testimony whereof I have signed my name to this specification in the presence of two subscribing witnesses.

WALTER ERBEN.
